CAMPER CAB

Charles Alden Sykes, Box 402, Rte. 1,
Nyssa, Oreg. 97913

Filed July 21, 1972, Ser. No. 273,883

Term of patent 14 years

Int. Cl. D12—10

U.S. Cl. D14—3 F

FIG. 1

FIG. 2

FIG. 3

FIG. 1 is a left rear perspective view of a camper cab showing my new design, with the canopy extension shown in closed position;

FIG. 2 is a right side elevational view thereof; and

FIG. 3 is a front elevational view with the right and left side canopy extension shown in open position.

I claim:

The ornamental design for a camper cab, substantially as shown and described.
